UNITED STATES PATENT OFFICE.

LE GRAND PARISH, OF NEW YORK, N. Y., ASSIGNOR, BY MESNE ASSIGNMENTS, TO
AMERICAN ARCH COMPANY, OF NEW YORK, N. Y., A CORPORATION OF DELAWARE.

LOCOMOTIVE-BOILER FURNACE.

1,138,056.

Specification of Letters Patent.

Patented May 4, 1915.

Application filed October 1, 1913. Serial No. 792,854.

To all whom it may concern:

Be it known that I, LE GRAND PARISH, a citizen of the United States, and a resident of New York city, county of New York, 5 and State of New York, have invented certain new and useful Improvements in Locomotive-Boiler Furnaces, of which the following is a specification.

My invention relates to improvements in 10 locomotive boiler furnaces and has particular reference to improvements in refractory baffles or deflecting walls for the fire boxes of locomotives.

The object of my invention is to provide a 15 refractory arch or baffle in a locomotive fire box which shall prevent the direct flow of the gases from the fuel bed to the flues, which shall effectually intermingle and intermix the rising fire box gases and which 20 shall increase the economical and efficient operation of the fire box as a steam producer.

A further object of my invention is to 25 provide an arch of novel construction which shall turn the gases out of their direct path from the fuel bed to the flues and cause them to flow rearwardly through the fire box in contact with the side sheets and then forwardly along the crown sheet, effecting the 30 several changes of flow in a manner to cause the complete intermingling and intermixing of the fire box gases to the end that the combustion may be entirely completed before the 35 gases escape from the fire box through the boiler flues.

A further object of my invention is to provide a refractory baffle or arch in a locomotive fire box which shall be composed of a plurality of refractory flat slab like bricks 40 which are supported in such related positions that an arch is provided which shall so direct and control the movements of the firebox gases that most economical and beneficial results shall result.

45 My invention resides in a locomotive firebox provided with a refractory arch having the functions above mentioned. My invention also resides in a locomotive firebox provided with an arch composed of a plurality 50 of flat slab refractory bricks and means for supporting the bricks to form an arch having the described functions.

My invention further consists in the combination with a locomotive fire box of a 55 transverse refractory arch therein having

outwardly and upwardly inclined side portions and a central portion which is V-shaped at the rear end and coincides with the inclination of the side portions and which is transversely flat at the forward 60 end and which gradually varies from end to end from the one extreme to the other.

My invention also consists in a fire box having a plurality of longitudinal arch tubes arranged in different planes and 65 adapted to support an arch of the form above described.

My invention also consists in a fire box in combination with a transverse V-shaped arch which gradually changes its shape from 70 end to end and consisting of a plurality of longitudinally extending panels supported at their meeting edges on longitudinally arranged tubes, the outer panels being arranged at a constant transverse inclination 75 from end to end and the middle panels changing their inclination from end to end between an inclination coincident with that of the side panels at the rear end to a horizontal position or substantially no inclination 80 in their forward ends.

My invention also consists in the several combinations and arrangements of parts and in the features of construction whereby the above and other objects are attained, and all 85 as hereinafter described and pointed out in the appended claims.

My invention will be more readily understood by reference to the accompanying drawings in which:

Figure 1 is a central vertical longitudinal section of a fire box equipped with a refractory arch in accordance with my invention; Figs. 2, 3, 4, 5, 6 and 7 are detailed transverse sections of the arch taken on the lines 95 2—2, 3—3, 4—4, 5—5, 6—6, and 7—7, respectively, of Fig. 1; and Fig. 8 is a vertical transverse section of the fire box showing a rear end elevation of the arch, and incidentally disclosing the preferred form of 100 the side sheet engaging ends of the bricks.

It should be understood that while I have limited the illustration of my invention to a so-called front arch my invention may be applied to the construction of arches in other positions in the fire box and having varying functions without departing from the spirit thereof. The principal function of the so-called front arch is to prevent the 105 direct flow of the gases of combustion from 110

the fuel bed to the flues and thereby cause the gases to flow backward and forward in the fire box, being thus detained in the fire box and being mixed or intermingled by the arch and caused to impinge upon the side sheets of the fire box.

My invention is particularly directed to enhancing the desirable qualities of such arches resulting in the more thorough intermingling and intermixing of the gases causing them to be positively impinged against the inner walls of the fire box and thereby causing them to give up their heat thereto and thus enhance the economical and efficient operation of the fire box.

A locomotive fire box A, as illustrated in the drawings, consists of a forward or flue sheet a^1 , a rear sheet a^2 , side sheets a^3 and a crown sheet a^4 . Flues a^5 lead forwardly from the flue sheet through the boiler, and the rear sheet is provided with a fuel door or opening a^6 . A grate a^7 is provided in the lower end of the box. I prefer to build up my arch out of a plurality of refractory members or bricks and for the purpose of supporting these members in position I provide the box with a plurality of water circulating or arch supporting tubes which are arranged longitudinally in the fire box and serve to increase the circulation of water in the boiler particularly between the forward and rear water legs thereof.

In the form of my invention illustrated in the drawings, I provide three of these tubes b^1 , b^2 and b^3 . The first two being substantially parallel and lying in the same plane and arranged symmetrically between the center and sides of the fire box, one at each side, and I arrange the third tube b^3 in such a manner that when the arch is supported upon the tubes, the shape of the arch or its cross section will gradually change from end to end. In the form of my invention illustrated the forward ends of the three tubes are arranged in substantially a single transverse line and the part of the center tube which supports the rear end of the arch is arranged out of line with and below the similar portions of the side tubes. On these tubes I build an arch C composed of a plurality of transverse rows D, of fire bricks E, each transverse row D comprising a central portion formed of two bricks d^1 which extend between and are supported by the three tubes, and side portions, each composed of a single brick d^2 supported at its inner end upon one of the side tubes and which leans against the adjacent side sheet in an upwardly and outwardly inclined position. Each of the bricks d^1 is provided in its inner end with a tube receiving socket or groove d^3 and at its outer end with a lower inclined surface d^4 adapted to rest upon the side tube.

Figs. 2 to 7 clearly illustrate the gradual

change of the shape of the arch from the forward end to the rear end and it will be clear that the arch is conformed in its transverse sectional shape to the relative positions of the three supporting tubes. The formation of the center bricks d^1 permits them to adjust themselves to the relative positions of the center tube and side tubes and rest securely thereon. A particularly valuable feature of my improved arch resides in the fact that as the gases of combustion rise from the fuel bed into contact with the lower surface of the arch and flow upwardly therebeneath, the rising gases are forced to roll outwardly into direct impinging contact with the side sheets of the fire box and this change in direction of the gases is gradually effected throughout the length of the arch by reason of the gradual change of shape thereof and whereby the gases are not only thoroughly intermingled and intermixed but are forced into contact with the side sheets of the fire box. The gases are thus caused to impinge against and flow in over and in contact with the side sheets of the fire box and thereby deliver the heat of combustion efficiently to the walls of the fire box.

Preferably I arrange the tubes and the sizes of the bricks so that the bricks of which the arch is built will not be so large but that they may be readily passed through the fire door and will not be too heavy but that they may be readily placed in position upon the tubes. I provide the undersurfaces of the arch bricks with shallow gas mixing recesses or pockets d^5 which serve to provide the arch with many small deflecting surfaces arranged at different angles. These pockets and deflecting surfaces enhance the gas mixing qualities of the arch.

In building my arch I first arrange the arch supporting tubes in the fire box as described, the side tubes being upwardly and rearwardly inclined at greater angles than the center tube. I then place a transverse row D of bricks upon the lower end of the tubes and in contact with the side sheets, this first row being substantially against or in contact with the flue sheet. I then place a second row D on the tubes above the first row in contact therewith and supported thereby. The center bricks of the first row are substantially horizontal, and the center bricks of the second row are inclined at a slight angle transversely of the fire box, each being inclined upwardly and outwardly from the center tube. In some instances where the arch is installed in small fire boxes these two transverse rows of fire bricks provide an arch of sufficient length to accomplish the desired results but usually it requires several transverse rows of the bricks and it is usually desirable to extend the arch rearwardly to substantially the middle of

the fire box as shown. The middle bricks of each succeeding row, rearwardly from the row which is in contact with the flue sheet, are inclined transversely at greater angles 5 until upon reaching the rear transverse row the middle bricks are inclined at substantially the same angles as the side bricks, as clearly shown in Fig. 7. This gradual change in relative position of the center 10 bricks of rows from a transverse horizontal position at the forward end to the maximum inclination at the rear end serves to gradually change the course of the rising fire box gases from a rearward flow beneath the 15 arch to an outward flow to and against the side sheets of the fire box and this change in direction causes the gases to roll over and over and thereby be mixed and impinged against the side sheets of the fire box. The 20 weight of the arch holds the several rows pressed forwardly into contact with each other and against the flue sheet on the inclined tubes and serves to retain the arch in position. The rising fire box gases in striking 25 the gradually changing surface of the arch are divided and forced outwardly in both directions, and having been thus divided and forced outwardly as they rise upwardly beneath the arch, are caused to be 30 further mixed and intermingled as they turn to flow forwardly through the fire box between the upper inclined surfaces of the arch and crown sheet, with the result that 35 the gases of combustion are not only held in the fire box longer than they would be were no arch used but they are so thoroughly mixed and intermingled that the oxygen present is brought into intimate contact with the highly heated fuel and thereby substantially 40 complete combustion is attained. In fact the whirling which is imparted to the two separate bodies of gases which flow upward in contact with the side sheets, one at one side and one at the other side of the 45 arch, forcibly causes these bodies of gas to thoroughly intermingle with each other as they are crowded together to pass through the triangular shaped opening or passage provided between the arch and the crown 50 sheet.

As many modifications of my invention will readily suggest themselves to one skilled in the art I do not limit or confine my invention to the specific structures herein 55 shown and described.

I claim:

1. A locomotive boiler fire box in combination with a refractory front arch therein extending from side sheet to side sheet, said arch being substantially V-shaped in cross section *i. e.* the sides thereof being upwardly and outwardly inclined at its rear end and gradually varying in shape from end to end.
2. A locomotive boiler fire box in combination with a refractory front arch therein, 60 extending from side sheet to side sheet, the forward end of the arch being substantially horizontal in its center portion and the rear end thereof being V-shaped *i. e.* the sides thereof being upwardly and outwardly inclined, and the arch varying gradually in shape from end to end.

extending from side sheet to side sheet, the forward end of the arch being substantially horizontal in its center portion and the rear end thereof being V-shaped *i. e.* the sides thereof being upwardly and outwardly inclined, and the arch varying gradually in shape from end to end. 70

3. A locomotive boiler fire box in combination with a refractory front arch therein comprising at its forward end a central section which is horizontal and upwardly and outwardly inclined end sections, and at its rear end side sections similarly inclined and a center section which has sides inclined coincident with the side sections, the intermediate central portion of the arch varying gradually in inclination from one end to the other. 75

4. In a locomotive firebox a transverse arch comprising a plurality of longitudinally arranged panels or sections, the side panels being symmetrically arranged and inclined upwardly and outwardly at a uniform angle from end to end, the center sections being also symmetrically arranged and varying in inclination from end to end the forward ends thereof being horizontal and the rear ends inclining upwardly and outwardly substantially coincident with the sides substantially as described. 80

5. A locomotive boiler fire box in combination with a longitudinally inclined refractory front arch therein, extending from side sheet to side sheet, having upwardly and outwardly inclined side portions extending 100 from front to rear and arranged at substantially a constant angle to the side sheets and a middle portion which is V-shaped and the sides of which vary in inclination transversely to the arch from end to end thereof the rear ends thereof being substantially in the planes of the sides. 105

6. A locomotive boiler fire box in combination with a longitudinally inclined refractory front arch therein extending from side sheet to side sheet having side portions extending upwardly and outwardly at a constant angle from end to end and having a middle portion which is V-shaped and whose sides are upwardly and outwardly inclined 110 at a greater angle at the rear end thereof than at the forward end thereof and the intermediate portion of which varies in transverse inclination from end to end. 115

7. A locomotive boiler fire box in combination with a plurality of arch supporting tubes, arranged longitudinally therein and inclined upwardly and rearwardly from the flue sheet, the members of said group being transversely symmetrically positioned, the side portions thereof occupying a common transverse plane and the middle portion varying therefrom, a refractory arch composed of a plurality of longitudinal sections supported by said tubes and the side sheets 120 125 130

of the fire box, the undersurface of the arch being substantially V-shaped *i. e.* being upwardly and outwardly inclined and the angle subtended by the sides gradually decreasing from the forward to the rear end of the arch.

5 In testimony whereof I have hereunto set

my hand, this 19th day of Sept., 1913, in the presence of two subscribing witnesses.

LE GRAND PARISH.
